UNITED STATES PATENT OFFICE.

WILLIAM PETZ, OF FIRTH, NEBRASKA.

VAPORIZER.

1,275,465.

Specification of Letters Patent. Patented Aug. 13, 1918.

Application filed March 20, 1917. Serial No. 156,159.

To all whom it may concern:

Be it known that I, WILLIAM PETZ, a citizen of the United States, residing at Firth, in the county of Lancaster and State 5 of Nebraska, have invented certain new and useful Improvements in Vaporizers, of which the following is a specification.

This invention relates to an improved vaporizer for internal combustion engines 10 and has as its primary object to provide a device of this character wherein crude oil or kerosene when used as a fuel for the engine may be effectually vaporized by the device prior to the introduction of the fuel 15 into the engine.

The invention has as a further object to provide a vaporizer wherein the exhaust from the engine will be carried through the device for heating and vaporizing the fuel 20 upon the passage thereof through the vaporizer.

The invention has as a further object to provide a vaporizer having a plurality of exhaust tubes leading therethrough for carrying the exhaust through the device and wherein the fuel will be led by a tortuous passage around the said tubes to strike thereagainst and thus become effectually vaporized.

30 And a still further object of the invention is to provide an arrangement wherein any of the fuel not vaporized upon initially coming in contact with the exhaust tubes of the device will be collected within cups 35 around the said tubes to thus finally become vaporized by the heat from the said tubes.

Other and incidental objects will appear as the description proceeds and in the drawings wherein I have illustrated the preferred embodiment of the invention and 40 wherein similar reference characters designate corresponding parts throughout the several views:

Figure 1 is a plan view partly in section 45 and illustrating my improved vaporizer in connection with a conventional type of internal combustion engine, this view particularly showing the arrangement of the carburetor employed and the hood for inclosing 50 the carburetor.

Fig. 2 is a horizontal sectional view taken through the lower portion of the vaporizer and particularly showing the fuel cups at the bottom ends of the exhaust tubes 55 through the vaporizer,

Fig. 3 is a vertical sectional view taken

on the line 3—3 of Fig. 2 particularly showing the arrangement of the transverse partitions of the vaporizer, and

Fig. 4 is a transverse sectional view taken 60 on the line 4—4 of Fig. 3.

In carrying out the invention, my improved vaporizer is formed with a preferably rectangular casing 10 having a top wall 11 and a bottom wall 12. Extending 65 transversely within the casing are spaced parallel partitions 13 and 14 respectively. These partitions divide the interior of the casing into a plurality of compartments and at one side of the casing, the side wall 70 thereof is bowed to provide a passage 15 connecting the adjacent ends of the middle and lowermost compartments while, at the opposite side of the casing, the wall thereof is bowed to provide a passage 16 connecting 75 the adjacent ends of the middle and uppermost compartments. Entering through the wall of the casing at the end of the lowermost compartment opposite the passage 15, is an intake passage 17 and extending from 80 the wall of the casing at the end of the uppermost compartment opposite the passage 16 is an outlet passage 18. As will thus be observed, the interior of the casing is divided into a tortuous fuel passage from 85 the intake 17 through the lowermost compartment of the casing, thence through the passage 15 to the middle compartment, thence through the middle compartment and through the passage 16 to the upper compartment 90 and thence through the upper compartment to the outlet passage 18.

Fitted through the casing are transversely spaced centrally arranged exhaust tubes 19 which extend vertically through the top 95 and bottom walls of the casing as well as through the partitions 13 and 14 and are arranged in substantially parallel relation. Projecting from one side wall of the casing between the exhaust tubes 19 are similar 100 exhaust tubes 20 and projecting from the opposite side wall of the casing between the exhaust tubes 19 are exhaust tubes 21 also similar to the exhaust tubes 19 and 20. The exhaust tubes 20 are arranged in substantially 105 parallel relation to extend vertically within the casing 10 and, as particularly shown in Fig. 3, open through the top and bottom walls 11 and 12 of the casing. Also, the exhaust tubes 21 are arranged substantially 110 parallel and open through the top and bottom walls 11 and 12. As will thus

be seen, the exhaust tubes 19, 20 and 21 are disposed in staggered relation and, as illustrated in the drawings, are each preferably rectangular in cross section. Formed in the 5 bottom wall 12 of the casing at the lower ends of the exhaust tubes are, as particularly shown in Figs. 2 and 3 of the drawings, a plurality of fuel cups 22. Preferably, the bottom wall 12 is pressed out to 10 form these cups.

Formed on the upper extremity of the casing 10 are flanges 23 and bolted or otherwise secured to these flanges is a pipe 24 adapted for connection with the exhaust 15 manifold or exhaust port of an engine 25, as particularly shown in Fig. 1, the internal combustion engine illustrated being of conventional design. Formed on the lower extremity of the casing 10 are flanges 26 20 and bolted or otherwise secured to these flanges is an exhaust pipe 27 which, intermediate its ends, is formed with an elbow 28. Fitted loosely around the outer extremity of the exhaust pipe 27 is an air intake 25 sleeve 29 which is open, at its outer end, and leading from the inner end of the said sleeve is the air passage 30 of a carbureter 31. This carbureter may be of any approved type and is provided with a fuel 30 pipe 32 preferably wound around the discharge pipe 27 so that the fuel within the said fuel pipe will be heated before being delivered to the carbureter. Extending from the carbureter 31 and connected with 35 the intake passage 17 of the casing 10, is a pipe 33 adapted to lead the fuel mixture from the carbureter into the casing. Secured to the outlet passage 18 of the casing is a fuel mixture pipe 34 adapted for connection with the intake manifold or other intake port of the engine 25 and having a throttle valve 35 of approved type interposed therein.

As illustrated in Fig. 1 of the drawings, 45 the carbureter 31 is mounted within the elbow 28 of the discharge pipe 27 and connected to the inner terminal of the said pipe, preferably by the bolts or other fastening devices securing the pipe to the casing 10, 50 is a hood or jacket 36 surrounding the elbow of the discharge pipe and inclosing the carbureter 31. This jacket will thus tend to retain the heat from the discharge pipe for heating the carbureter and consequently 55 the fuel as it is delivered thereto.

As will now be understood, exhaust from the engine 25 will pass out through the pipe 24 and thence through the exhaust tubes 19, 20 and 21 in the casing 10 to finally discharge 60 through the pipe 27. The heated gases of the exhaust will, therefore, act to heat the exhaust tubes 19, 20 and 21 and to at all times maintain these tubes hot. Fuel flowing through the pipe 32 will, as previously mentioned, first be heated from the

exhaust pipe 27 and will then flow into the carbureter 31 which is in turn heated by the heat from within the jacket 36. This preliminary heating of the fuel will, of course, tend to make the fuel easily volatilized. The air supplied to the carbureter being drawn in through the sleeve 29 will be heated from the exhaust pipe 27 so that this heated air upon passing through the carbureter 31 will further tend to volatilize the fuel. From the carbureter, the fuel mixture will enter the lower compartment of the vaporizer and will then follow the tortuous fuel mixture passage therethrough to be discharged through the pipe 34 to the engine.

Attention is now directed to the fact that when the fuel mixture enters the lower compartment of the vaporizer, the mixture will, owing to the character of the fuel, have a 85 tendency toward denseness or humidity and will, in this condition, be brought into contact with the exhaust tubes 19, 20 and 21. Upon striking the flat sides of these tubes, the coarser particles of the mixture or improperly vaporized particles thereof will collect upon the said tubes and run down the sides thereof into the cups 22. As the fuel mixture continues through the lower compartment of the vaporizer, the mixture 90 will, as it is drawn around the several exhaust tubes, thus be dried out and heated by the said tubes to be delivered into the middle compartment of the vaporizer. Upon thus entering this compartment, the 95 fuel mixture will then again be drawn around the said exhaust tubes 19, 20 and 21 to be further dried out and effectually volatilized by the heat from the said tubes. From the middle compartment, the fuel 100 mixture will then pass into the upper compartment of the vaporizer to flow around the upper ends of the exhaust tubes and be still further heated and effectually transformed into a dry heated homogeneous gas 105 for delivery to the engine. The fuel mixture collecting within the cups 22 will, by coming in contact with the heated walls of the exhaust pipes also become vaporized in due course to thence follow the tortuous 110 passage through the vaporizer with the other gas flowing therethrough.

It will, therefore, be seen that I provide a particularly efficient arrangement for the purpose set forth and a construction where- 115 in the fuel mixture upon first entering the vaporizer will be initially acted upon to dry the mixture out and volatilize the mixture; will then be acted upon to further dry the mixture and will be finally acted 120 upon to turn the mixture into a dry heated homogeneous gas. In this connection, at- 125 tention is particularly directed to the ar- rangement of the exhaust tubes 19, 20 and 21. It will be observed that the fuel mix- 130

ture upon first entering any one of the three compartments of the vaporizer will initially strike against one of the centrally arranged tubes 19. The fuel mixture must then flow 5 around this tube and then inwardly away from the side walls of the casing 10 of the device to pass between the confronting ends of the adjacent pair of oppositely disposed tubes 20 and 21 respectively. The fuel mixture 10 will thus be drawn away from the side walls of the casing which, in not being directly heated, would have a tendency to cool or condense the fuel mixture. Upon passing between the said pair of oppositely disposed tubes 15 and 21 respectively, the fuel mixture will, of course, strike against the said tubes to be heated thereby and will then come in contact with the next adjacent centrally disposed tube 19. The fuel mixture 20 will then be caused to flow around this tube and again be drawn inwardly away from the side walls of the casing between the confronting ends of the next adjacent pair of oppositely disposed tubes 20 and 21 25 to be heated therefrom when the fuel mixture will finally strike the last of the centrally disposed tubes 19. Accordingly, as the fuel mixture flows through each of the compartments of the vaporizer, the mixture 30 will be caused to pass between the exhaust tubes in such manner that the mixture will be effectually heated and volatilized while, at the same time, the fuel mixture will, owing to the disposition of the exhaust tubes 35 with respect to each other, be drawn away from the side walls of the casing to thus minimize the cooling of the mixture from the said walls.

Having thus described the invention, what 40 is claimed as new is:

1. A device of the character described in-

cluding a casing having top and bottom walls and provided with inlet and outlet passages, a partition within the casing and defining a tortuous fuel passage therein between said first mentioned passages, an exhaust tube fitted through the top and bottom walls of the casing and through said partition to project into the fuel passage, and a fuel cup at the lower extremity of 50 said exhaust tube.

2. A device of the character described including a casing having top and bottom walls and provided with inlet and outlet passages, a partition within the casing and defining a tortuous fuel passage therein between said first mentioned passages, an exhaust tube fitted through the top and bottom walls and through said partition to project into the fuel passage, and a fuel cup 55 formed from the bottom wall at the lower extremity of said exhaust tube.

3. In a device of the character described, the combination with a vaporizer having an exhaust pipe provided with an elbow, of a 60 carbureter mounted in said elbow and communicating with the vaporizer, an open ended sleeve surrounding the exhaust pipe and communicating with the air inlet passage of the carbureter, and a hood connected 65 with the vaporizer and arranged to inclose the said elbow and surround the carbureter.

4. In a device of the character described, the combination with a vaporizer having an exhaust pipe provided with an elbow, of a 70 carbureter mounted in said elbow and communicating with the vaporizer, and a hood connected with the vaporizer and coacting with the said elbow to surround the carbureter.

In testimony whereof I affix my signature.

WILLIAM PETZ. [L.S.]
